UNITED STATES PATENT OFFICE.

VICTOR LYNNEQUEST, OF OMAHA, NEBRASKA, ASSIGNOR OF ONE-THIRD TO RAYMOND J. MCKENNA AND ONE-THIRD TO RODERICK LE BRON, BOTH OF OMAHA, NEBRASKA.

BED-MOVEMENT.

1,095,120.

Specification of Letters Patent. Patented Apr. 28, 1914.

Application filed November 22, 1912. Serial No. 733,014.

To all whom it may concern:

Be it known that I, VICTOR LYNNEQUEST, a citizen of the United States, and a resident of Omaha, in the county of Douglas 5 and State of Nebraska, have invented certain new and useful Improvements in Bed-Movements, of which the following is a specification.

My invention relates to printing presses, 10 and especially to presses of the bed-and-cylinder type or those in which the type-forms are disposed on a bed which has a reciprocating movement in a horizontal plane, and the paper is pressed onto the type by a cylinder which makes one revolution during the 15 making of the impression and while its surface is moving with the bed, and is then raised out of contact or away from the bed and makes a second revolution while the bed 20 moves back to the initial position, the paper being discharged from the cylinder during the second revolution thereof.

My invention relates particularly to the driving or actuating mechanism for presses 25 of the described class, and it is the object thereof to provide a simple, comparatively inexpensive and durable driving mechanism, capable of operation at high speed without causing excessive jarring or vibration, and 30 an improved trip mechanism or means for preventing an impression being made should the paper not be properly fed to the cylinder.

Constructions embodying my invention 35 are shown in the accompanying drawings, in which—

Figure 1 is a side view of part of a press with my actuating mechanism applied thereto, Fig. 2 is an end view of the same, Fig. 40 3 is a vertical longitudinal sectional view taken on the plane of the line $x-x$ of Fig. 2, and Fig. 4 is a detail side view of the cam-bar.

The parts of the press shown which are 45 essentially of ordinary construction and arrangement are the frame 1, the cylinder 2, the feed-table 3, the bed 4, the bed track-rollers 5, and the toggle mechanism for raising and lowering the cylinder. Said mechanism 50 comprises the vertically-slidable rods 6 which extend downwardly from the cylinder-shaft bearings, sliding heads 7 arranged in vertical guideways in the frame

and connected to the lower ends of said rods, 55 springs 8 arranged beneath the heads 7, toggle-links 9 connecting the heads 7 and the frame, and a transverse shaft 10 connecting the toggle-links. The cylinder is lowered to the "contact" or impression position by movement of the shaft 10 such as 60 to bring the toggle-links into vertical alignment with each other, and is raised out of the impression position by movement of the shaft 10 such as to throw the toggle-links 65 out of the vertically-aligned position.

The toggle-shaft 10 is actuated by means of a cam-bar 11 which engages the central part of the shaft, the bar having an arcuate slot 12 therein through which the toggle-shaft passes, and near one end having a longitudinal slot 13 through which passes a transverse shaft 14 suitably journaled in the frame. On said shaft 14 is a cam 15 which engages rollers 16 carried on the bar 11 and imparts to the bar an intermittent longitudinal reciprocating movement. The cam-bar has a tail-portion 17 which is adapted to engage the end of the trip-lever 18 so that when the outer end of the trip-lever is depressed the cam-bar is raised thereby. The 70 toggle-shaft 10 is normally in the upper portion of the arcuate slot 12, but when the cam-bar is raised by depressing the trip-lever the shaft passes into the lower part of said slot, and the slot is so formed that the 75 result of this is to shorten the effective length of the cam-bar between the shafts 10 and 14 and cause the cylinder to be raised slightly higher than when the cam-bar is in the normal position. As the amount of vertical movement imparted to the cylinder by the cam 15 remains practically constant, the increased lifting of the cylinder results in it being kept out of contact with the type-form on the bed as long as the trip-lever is 80 held down and the cam-bar held in the raised position. The cylinder will continue, however, to be raised and lowered at each alternate revolution thereof.

The cylinder-shaft 19 and the shaft 14 85 are both driven constantly, in the directions indicated, by means of a gear-train which connects them with the main drive-shaft 20, as follows: The shaft 20 carries a pulley 21 90 which is connected by belt with a suitable 95 source of power, such as an electric motor.

- On the shaft 20 is also carried a pinion 22 which meshes with a gear 23 carried on the outer end of a stub-shaft 24 journaled in the side-member of the frame 1. On the inner end of the shaft 24 is a pinion 25 which meshes with a gear 26 carried on the shaft 14. An intermediate gear 27 is mounted on a stud 28 at the side of the frame and meshes with the gear 23 and the gear 29 carried on the end of the cylinder-shaft. The intermediate gear 27 is so arranged with reference to the cylinder-gear 29 that the vertical movements of the latter will not interfere with the rotary driving connection. The ratios of the gear-train are such that the shaft 14 makes one revolution to each two revolutions of the cylinder and the gear 23 makes one and a half revolutions to each revolution of the cylinder-gear.
- On the lower side of the reciprocating bed 4 are secured racks 30 which are constantly in mesh with gears 31 carried on a transverse shaft 32 journaled in the frame beneath and parallel to the cylinder-shaft.
- On the end of the shaft 32 is a gear 33 which is adapted to mesh with the cylinder-gear 29 when the cylinder is in its lower position or in the partially lowered position permitted when the trip-lever is operated to raise the cam-bar, as before described. The vertical movements imparted to the cylinder by the toggle mechanism are such that when the cylinder is raised the gears 29 and 33 pass out of mesh.
- On the shaft 14 is a segmental or mutilated gear 34 which has teeth on approximately half of its peripheral face, the same being adapted to mesh with a gear 35 carried on the bed-drive shaft 32. A gear-segment 36 is pivoted on the frame, as shown, and is connected with a crank-pin 37 on the gear 23 by means of a suitable connecting-rod 38, so that the rotation of said gear 23 imparts a reciprocating movement to the said segment 36. The teeth of the segment are adapted to mesh with a segment 39 secured on the outer side of the gear 33, as shown.

Referring now to the operation of the described mechanism, during the movement of the bed 4 forwardly, or in the direction indicated in Fig. 3, the cylinder is in the lowered position so that the paper carried thereby will be pressed against the type-form on the bed and receive an impression therefrom. The cylinder being in the lowered position, the cylinder-gear 29 and the gear 33 are in mesh so that the shaft 32 and the bed are in direct geared connection with the cylinder. During this phase of the operation the driving connection from the main drive-shaft 20 to the bed is made through the following members of the actuating mechanism: the pinion 22, gear 23, shaft 24, pinion 25, gear 26, shaft 14, gear 34, gear 35, shaft 32, gears 31 and racks 30. As the bed approaches the forward limit of its stroke, or at about the position shown in Fig. 3, the cylinder is raised by the toggle-mechanism so that the gears 29 and 33 pass out of mesh.

Just prior to this, however, the segment 39 on the gear 33 approaches the position shown in Fig. 1, the crank-pin on the gear 23 is moving upwardly and actuating the segment 36 in like direction, and the segments 36 and 39 thus come into mesh with each other before the gears 29 and 33 are entirely out of mesh, as shown in Fig. 1. As the crank-pin 37 passes over the upper dead-center, with reference to the movement of the connecting-rod 38, the movement of the "walking-segment" 36 is stopped momentarily and then commences in the opposite or downward direction. In consequence of this movement, the movement of the gear 33, of the shaft 32 and of the bed is gradually stopped and then reversed in direction. In large presses the stopping of the movement of the bed may be assisted by a pneumatic buffer-cylinder 40 such as is ordinarily employed in presses of this class. After the rearward movement of the bed has been started by the downward movement of the walking-segment 36, the mutilated-gear 34 comes into mesh with the gear 35 so that the driving of the bed rearwardly is continued after the segments 36 and 39 pass out of mesh. During this phase of the operation the driving connection from the shaft 20 to the bed is made through the following members of the actuating mechanism: the pinion 22, gear 23, shaft 24, pinion 25, gear 26, shaft 14, gear 34, gear 35, shaft 32, gears 31 and racks 30. As the bed approaches the rearward limit of its movement, and just before the mutilated-gear 34 passes out of mesh with the gear 35, the gear 33 is moving in the direction of the dotted arrow A in Fig. 1 and the segment 39 is moving downwardly at the side of the gear adjacent to the crank-gear 23. At the same time, the crank-pin 37 is moving downwardly at a position about diametrically opposite to the position thereof in Fig. 1 and is thus actuating the walking-segment 36 in a downward direction. In consequence the walking-segment and the segment 39 pass into mesh while they are both moving in the same direction, and are in mesh before the gears 34 and 35 pass out of mesh. As the crank-pin 37 passes across the lower dead-center the movement of the shaft 32 and the bed is stopped and then reversed, as before described, except that all the movements are in the opposite directions. After the forward movement of the bed has been started by the driving connection formed through the walking-segment, the cylinder is lowered by the action of the cam and toggle mechanism, so that the gears 29 and 33 pass into mesh again.

mesh before the segments 36 and 39 pass out of mesh. The forward movement of the bed is then completed with the driving connections as at first described.

5 In connection with the operation of the mechanism it should be noted that in making the various changes in the driving connections to the shaft 32, wherein gears pass into and out of mesh, in each case the gears come into mesh while both are moving in the same direction and at substantially the same speed. Thus, both times that the walking-segment 36 engages the segment 39, said segments pass into mesh with a rolling 10 movement, both moving in the same direction and at practically the same speed, so that the engagement occurs without shock or jar. Similarly the engagement between the mutilated gear 34 and the gear 35 occurs 15 when they are moving in the same direction. Similarly also, the engagement of the cylinder-gear 29 and the gear 33 occurs when the latter gear has been started to move in the same direction as the cylinder-gear and 20 has reached about the same speed.

With reference to the crank-gear 23 it should be noted that the same forms an element of the gear-train connection from the driving-shaft 20 to both the cylinder-gear 29 and the shaft 14, and also, by virtue of the speed ratio between it and the cylinder-gear, it is enabled to actuate the walking-segment so that the same is moved in the appropriate directions to cause in sequence 30 the desired retardation, stopping and reversing of the movement of the bed at each end of its stroke. The reversing of the movement of the bed, being caused by a crank-driven member during the passage of 35 the crank-pin across a dead-center, takes place smoothly and easily so as not to cause excessive jarring or vibration of the press. This enables the press to be operated at a relatively high speed, and in small and light 40 presses it is possible to dispense with the usual buffer-cylinders for slowing down the movement of the bed at the ends of its stroke.

Now, having described my invention, 50 what I claim and desire to secure by Letters Patent is:

1. In a bed-and-cylinder printing press, a cylinder-gear, a bed-drive shaft, a main drive-shaft, gearing connecting the main drive-shaft and cylinder-gear for actuating the latter continuously, a cam-shaft, means actuated thereby for lifting the cylinder during the alternate revolutions thereof, a gear on the bed-drive shaft arranged to engage the cylinder-gear when the cylinder is 55 in lowered position, a mutilated gear on the cam-shaft, a gear on the bed-drive shaft engageable by said mutilated gear so as to be driven thereby while the cylinder is lifted, 60 a crank-actuated oscillating member, and 65

means for connecting the same with the bed-drive shaft as the bed approaches each limit of its movement.

2. In a press of the class described, a cylinder, a driving shaft, gearing connecting said shaft and the cylinder for continuously rotating the latter in one direction, means for elevating the cylinder during alternate revolutions thereof, a bed-drive shaft, actuating means for said shaft connected with the cylinder when the same is in lowered position and disconnected from the cylinder by elevation thereof, actuating means adapted to connect the driving shaft and bed-drive shaft during the time that the latter is disconnected from the cylinder, a crank-driven reciprocating element, and means for connecting the same with the bed-drive shaft intermittently to reverse the direction of movement of the said shaft. 85

3. In a press of the class described, a reciprocating bed, a bed-drive shaft gear-connected therewith, two gears fixedly secured on the bed-drive shaft, continuously-moving actuating means engageable with one of said gears to actuate the bed in one direction, continuously-moving actuating means engageable with the other gear to move the bed in the other direction, an oscillating actuating element, means for connecting said element with the bed-drive shaft as the bed approaches each limit of its movement so that the movement of the bed will be thereby reversed simultaneously with the reversal movement of the oscillating element, 100 and primary actuating means operatively connected with the several parts, whereby the continuously-moving actuating means are engaged with the respective gears on the bed-drive shaft alternately after the successive reversals of movement of the bed. 105

4. In a bed-and-cylinder printing press, a cylinder shaft, a reciprocating bed, a main drive-shaft, a cam-shaft, gearing connecting the main drive-shaft with the cylinder-shaft 110 and cam-shaft to rotate them continuously, a bed drive-shaft gear-connected with the bed, a gear carried by said shaft, a gear carried by the cylinder-shaft and engageable with the gear on the bed-drive shaft to actuate the same, means actuated by the cam-shaft for elevating the cylinder-shaft to disengage said gears during alternate revolutions of the cylinder-shaft, a mutilated gear on the cam-shaft, a gear on the bed-drive 120 shaft engageable by said mutilated gear during a part of the time that the cylinder-shaft is raised, and means for reversing the direction of movement of the bed-drive shaft before each engagement of the gears on the bed-drive shaft by the mutilated gear and by the gear on the cylinder-shaft. 125

5. In a press of the class described, a reciprocating bed, a bed-drive shaft gear-connected therewith, a main drive-shaft, a cylin- 130

- der, gearing connecting the main drive-shaft and cylinder for rotating the latter continuously in one direction, means for raising and lowering the cylinder during alternate revolutions thereof, actuating means for connecting the cylinder and bed-drive shaft while the cylinder is in lowered position, said actuating means being disconnected by raising of the cylinder, actuating means connecting the main drive-shaft and bed-drive shaft intermittently, whereby the latter is driven while the cylinder is in raised position, a crank-driven reciprocating member, and means for connecting the same with the bed-drive shaft during the raising and lowering of the cylinder, said member moving in alternating directions during its successive periods of connection with the bed-drive shaft.
- 20 6. In a press of the class described, a reciprocating bed, a bed-drive shaft connected therewith, a cylinder adjacent to the bed, means for continuously driving the cylinder, said means including a cylinder-gear fixedly connected therewith, a gear secured on the bed-drive shaft and directly engageable with the cylinder-gear whereby said shaft may be driven in one direction by said cylinder-gear, means for raising the cylinder during alternate revolutions thereof to disengage the cylinder-gear from said gear on the bed-drive shaft, and means controlling the cylin-

der-raising means whereby the normal distances between the bed and cylinder may be increased.

7. In a press of the class described, a reciprocating bed, a bed-drive shaft connected therewith, a cylinder adjacent to the bed, means for driving the cylinder continuously, a cylinder-gear fixedly connected therewith, a gear secured to the bed-drive shaft and directly engageable with the cylinder-gear whereby said shaft may be driven in one direction by said cylinder-gear, means for raising the cylinder to disengage the cylinder-gear from said gear on the bed-drive shaft, means for reversing the direction of movement of the bed-drive shaft before and after each engagement of said gears, means for actuating the bed-drive shaft in the direction opposite to that in which it is driven by the cylinder-gear, and means controlling the cylinder-raising means whereby the normal distances between the bed and cylinder may be increased without preventing engagement of the cylinder-gear and the gear on the bed-drive shaft.

In testimony whereof I have hereunto subscribed my name in the presence of two witnesses.

VICTOR LYNNEQUEST.
